RETURN FLOW CARBURETOR

Thomas M. Ball, Bloomfield Hills, Mich., assignor to Chrysler Corporation, Highland Park, Mich., a corporation of Delaware

Filed July 28, 1959, Ser. No. 830,007

6 Claims. (Cl. 261—27)

This invention relates to improvements in a carburetor particularly adapted for use with an automobile internal combustion engine. This application is a continuation-in-part of co-pending application Serial No. 861,529, filed May 28, 1959, now Patent No. 3,078,077.

In conventional carburetors, a float controlled fuel inlet needle valve is employed to regulate the fuel level in the carburetor fuel bowl. Small dirt particles sometimes interfere with effective operation of the valve, as for example by becoming lodged between mating valve seats which otherwise cooperate to regulate the fuel flow into the fuel bowl. Also the floats require considerable size in order to be effective because of the comparatively low specific gravity of the fuel. In consequence the size of the fuel bowl must be appreciably larger than is otherwise desired.

An important object of the present invention is to provide an improved carburetor which avoids the foregoing objections and in particular to provide a floatless carburetor which does not require a fuel inlet needle valve.

Another object is to provide such a construction including an overflow standpipe in the fuel bowl having an upper opening which determines the maximum fuel level in the bowl. A fuel inlet pump is provided to pump fuel into the bowl at a rate in excess of demand. The excess fuel overflows into the standpipe and is returned to the fuel tank. In order to overcome adverse grade conditions which prevent the excess fuel from returning to the tank by gravity flow, a scavenging pump is provided in the fuel return line between the overflow standpipe and the tank.

Among other advantages of the above structure, elimination of the necessarily large float enables utilization of a comparatively small fuel bowl closely adjacent the inlet air induction conduits of a multiple barrel carburetor, for example. The small fuel bowl thus located is less sensitive to grade and inertial effects and enables uniform fuel distribution to each of the several induction conduits. Also recirculation of the fuel drives off its more volatile fuel fractions and thereby minimizes some of the problems of the conventional float controlled carburetor, as for example those concerned with vapor formation.

In order to provide adequate fuel during maximum engine speed at wide open throttle, a fuel inlet pump is provided which delivers an excess supply of fuel to the fuel bowl during all operating conditions of the engine. When the throttle is suddenly closed while the engine is still operating at high speed, unless some provision is made to the contrary, a major portion of the fuel supplied to the fuel bowl will be recirculated. In general the life of a fuel pump and in particular the life of an engine driven diaphragm type pump, which is preferred for supplying fuel in the quantity required and at a substantially uniform pressure regardless of changes in engine speed, depends upon the quantity of fuel pumped.

For the above reasons, as well as the desirability of conserving power in an automobile engine and of minimizing fuel heating by excessive recirculation, another object of the present invention is to provide improved simple and highly effective means for supplying fuel to the fuel bowl in reasonable and safe amounts related to engine requirements.

Another object is to provide a carburetor and diaphragm fuel pump combination of the type described wherein the pump comprises a pumping chamber having a movable diaphragm defining one wall thereof. The pumping chamber is provided with check valve controlled inlet and discharge ports in communication with a fuel tank and with the fuel bowl respectively and operative so that during movement of the diaphragm in one direction in an intake stroke to enlarge the volume of the pumping chamber, fuel is drawn from the tank into the pumping chamber. During movement of the diaphragm in the opposite direction in a pumping stroke, fuel is discharged from the pumping chamber into the fuel bowl. The diaphragm is secured to a plunger arm for actuation thereby. A pumping spring under compression between the diaphragm and a fixed portion of the pump mechanism yielding urges the diaphragm in said opposite direction to cause the pumping stroke. A pivotal arm engageable with a rotating cam driven by the automobile engine to be pivotally oscillated thereby is also engageable with the plunger to move the latter in said one direction against the force of the pumping spring to compress the latter. The pivotal arm is also freely engageable with the plunger so that during the reverse pivotal movement of the arm, the latter will move independently of the plunger and release the diaphragm for spring urged pumping movement in said opposite direction, but will not positively urge movement of the diaphragm in said opposite direction. In consequence, the pumping force will result entirely from the compressed pumping spring and will be substantially constant regardless of the speed of the engine or of the pivotally oscillated arm.

Other and more specific objects are to provide such a diaphragm pump and carburetor combination having means for varying the pumping stroke of the diaphragm in said opposite direction by a direct linkage with the throttle actuating mechanism, or by pressure actuated means connected with the engine air inlet induction system or with the discharge side of the scavenging pump.

Other objects of this invention will appear in the following description and appended claims, reference being had to the accompanying drawings forming a part of this specification wherein like reference characters designate corresponding parts in the several views.

FIGURE 1 is a schematic mid-sectional view of a floatless return flow carburetor and pump embodying the present invention showing means actuated by induction conduit pressure downstream of the throttle valve for controlling the diaphragm pumping stroke.

FIGURE 2 is a fragmentary view similar to FIGURE 1 illustrating a modification.

FIGURE 3 is a view similar to FIGURE 1, but showing means actuated by induction conduit pressure at the venturi throat for controlling the diaphragm stroke.

FIGURE 4 is a fragmentary view similar to FIGURE 3 illustrating a modification.

FIGURE 5 is a view similar to FIGURE 1, but showing means actuated by the scavenging pump discharge pressure for controlling the diaphragm stroke.

FIGURE 6 is a fragmentary view similar to FIGURE 5 illustrating a modification.

FIGURE 7 is a view similar to FIGURE 1 but showing a mechanical linkage with the throttle mechanism for controlling the diaphragm stroke.

FIGURE 8 is a view similar to FIGURE 7 illustrating a modification.

It is to be understood that the invention is not limited in its application to the details of construction and arrangement of parts illustrated in the accompanying drawings, since the invention is capable of other embodiments and of being practiced or carried out in various ways. Also

it is to be understood that the phraseology or terminology employed herein is for the purpose of description and not of limitation.

Referring to FIGURE 1, the carburetor shown comprises a cast housing formed to provide an air inlet induction conduit including a venturi portion 10 having a restricted venturi 11 at its upper portion and a throttle blade 12 pivotally mounted on a shaft 13 at a lower portion usually referred to as the throttle body. An upper portion of the casting is formed to provide an air horn 14 adapted to be connected with the usual air filter and opening at its downstream end into the venturi 11 to supply air thereto. The casting portions 10 and 14 are suitably secured together, as for example by screws not shown, and comprise an upper portion of the air inlet and fuel mixing induction system which extends downstream of the throttle valve 12 and discharges into the usual engine cylinders in a conventional manner.

Integral with the casting 10 in the present instance is a fuel bowl casting 15 containing an annular chamber or fuel bowl 16 enclosing a cylindrical standpipe or wier 17 which also serves as an acceleration pump cylinder containing a plunger 18 reciprocable in its lower portion and secured to a plunger shaft 19 for actuation thereby. Where desired the shaft 19 is connected by suitable linkage with a pedal operated accelerator mechanism which controls the opening and closing of valve 12 to operate conjointly therewith. Upon upward movement of plunger 18, fuel is drawn into the lower portion of chamber 17 via conduit 20 in communication with the bowl 16. A suitable check valve illustrated schematically as a ball-check element 21 normally seats at the mouth of the duct 20 opening into the lower portion of chamber 17 to prevent loss of fuel therefrom but is raised from its seat by the fuel flow into chamber 17 on the upstroke of plunger 18. Upon downward movement of plunger 18 the fuel is forced from chamber 17 into the induction conduit via acceleration fuel conduit 22, ball check valve 23, and nozzle 24 which latter discharges into the induction conduit at a location immediately above the throat of venturi 11. The check valve 23 is schematically illustrated as a ball normally urged by a spring to a seated position closing nozzle 24 from the interior of chamber 17, the ball being readily movable upward against the tension of its seating spring by the acceleration fuel pressure upon downward movement of plunger 18. The main fuel to the engine is supplied via duct 25 which opens at its lower end through metering port 26 into the fuel bowl 16 and communicates at its upper end with a fuel nozzle 27 having its discharge orifice located within the throat of venturi 11.

In accordance with the structure described thus far, fuel entering the body 16 in excess of engine requirements overflows the upper edge of standpipe 17 which thereby maintains the fuel in the bowl 16 at a predetermined maximum level determined by the effective height of the standpipe 17 without recourse to a float operated mechanism. Fuel is supplied to the bowl 16 from a suitable fuel tank via conduit 28.

A multiple piece fuel pump housing 37 comprising an upper dome 38 and a lower basin 39 cooperate with diaphragms 40 and 41 respectively to provide an inlet fuel pumping or working chamber 42 and an exhaust fuel pumping or scavenging chamber 43. Springs 44 and 45 under compression between portions of housing 37 and diaphragms 40 and 41 respectively urge the former diaphragm upwardly and the latter diaphragm downwardly to effect the pumping strokes for the respective chambers 42 and 43.

The upper working chamber 42 comprises a portion of supply duct 28 which communicates upstream of chamber 42 with the fuel tank. Fuel enters and leaves chamber 42 via an inlet port 46 and a discharge port 47 associated with check valves 48 and 49 respectively. Upon downward movement of diaphragm 40 as explained be-

low, fuel is drawn in the direction of the arrow 28a from the tank and through inlet port 46 into working chamber 42. During this operation ball valve 48 is forced from its seat at port 46 by the fuel flow, and ball valve 49 seats at the discharge port 47 to close the latter from the fuel bowl 16. Upon upward movement of diaphragm 40, ball valve 48 is caused to seat at port 46 to close the working chamber 42 from the fuel tank. During this operation, the pressure exerted in chamber 42 unseats ball valve 49 from port 47 and supplies fuel via conduit 28 to the fuel bowl 16. The spaces at the sides of the diaphragms 40 and 41 opposite chambers 42 and 43 respectively are vented to the atmosphere by ducts 50 and 51 to facilitate the pump operation.

15 Fuel is returned in the direction of arrow 52a from standpipe 17 to the fuel tank via fuel return conduit 52 which includes chamber 43 as a portion thereof. Upstream, the conduit 52 communicates with standpipe 17 at a location above the uppermost limit of movement of plunger 18. The return fuel enters chamber 43 via port 53 and discharges from chamber 43 via port 54. Ball check valves 55 and 56 are associated with ports 53 and 54 respectively, so that upon upward movement of diaphragm 41 as described below, ball 56 seats against port 54 to close chamber 43 from the fuel tank. During this operation, ball 55 is unseated from port 53 to open communication between chamber 43 and standpipe 17 and to draw fuel from the latter. Upon downward movement of diaphragm 41, ball 55 is seated against port 53 to close chamber 43 from standpipe 17. Simultaneously ball 56 is unseated from port 54 by the pressure in chamber 43 to discharge fuel from the latter in the direction of arrow 52a to the tank. Movement limiting pins in the conduits 28 and 52 associated with the ball valves 48, 49, 55 and 56 prevent undue movement of the balls from their associated ports. Inasmuch as the check valves are well-known, these are merely shown schematically and are not discussed in further detail.

40 Actuation of the diaphragms 40 and 41 is accomplished by driving shafts 57 and 58 connected to these diaphragms and terminating in enlarged heads 59 and 60 respectively. Pivotal levers 61 and 62 are pivoted on housing 37 at locations 63 and 64 respectively between their ends. Each lever has one end engaged with a rotating eccentric cam 65 mounted on a shaft 66 driven by the automobile engine. The opposite ends of the levers 61 and 62 are provided with oversized openings 67 and 68 through which the rods 57 and 58 extend freely to enable their relative sliding movement with respect to the levers 61 and 62 until the levers engage the enlarged heads 59 and 60.

55 Upon operation of the automobile engine, shaft 66 is rotated to turn cam 65 and thereby cause pivoting of levers 61 and 62. Upon clockwise pivoting of lever 61, or counterclockwise pivoting of lever 62, the head 59 or 60 is engaged to pull the associated rod 57 or 58 in the direction to compress the spring 44 or 45 as the case might be. Upon counterclockwise pivoting of lever 61 and clockwise pivoting of lever 62, the oversized openings 67 and 68 enable the levers to swing independently of the shafts 57 and 58, whereupon springs 44 and 45 are released to force diaphragms 40 and 41 in pumping actions toward the associated dome 38 and basin 39. The pivotal action of levers 61 and 62 merely compresses the springs 44 and 45 alternately, which latter then exert resilient force to effect the pumping action of the associated diaphragms 40 and 41. In consequence, fuel is discharged from chamber 42 at a uniform optimum pressure determined by the force of spring 44. Upon the upward stroke urged pumping stroke of diaphragm 40, fuel is discharged via port 47 to fuel bowl 16. All fuel in excess of engine requirements overflows the standpipe 17 and returns by conduit 52 to chamber 43 via port 53, whereupon the fuel is pumped to the fuel tank by downward stroke urged pumping movement of diaphragm 41.

In order to prevent too great an excess of fuel from being pumped to fuel bowl 16 when the engine is operating at comparatively light load, means are provided for limiting the maximum movement of diaphragm 40 during the spring urged pumping stroke. As illustrated in FIGURE 1, eccentric cam 69 is keyed to a pivot shaft 70 mounted within housing 37 and extending to the exterior thereof. Keyed to shaft 70 to pivot therewith and with cam 69 is a swinging lever 71 which extends upward at a location exteriorly of housing 37 and is pivotally secured at its upper end at 72 to the outer end of a plunger shaft 73. Cam 69 directly overlies the central portion of diaphragm 40 and is shaped so that upon being pivoted counterclockwise in FIGURE 1, diaphragm 40 will be depressed. Plunger 73 extends freely through an air vent and guide opening 74 in the wall of a pressure chamber 75. The latter is partitioned by a diaphragm 76 which is normally urged to the right in FIGURE 1 by coil spring 77 disposed between housing 75 and diaphragm 76.

Variations in engine fuel requirements are detected by conduit 78 which connects pressure chamber 75 at the left of diaphragm 76 with the low pressure region of induction conduit 10 downstream of throttle valve 12. When the engine is operating at light load and throttle valve 12 is partially closed, the low pressure applied through conduit 78 to the left side of diaphragm 76 will cause the latter to be forced to the left against the pressure of spring 77, thereby swinging lever 71 and cam 69 counterclockwise about the axis of shaft 70 to reduce the pumping stroke of diaphragm 40.

In the converse action, as throttle valve 12 progressively moves toward an open position, the pressure conveyed to the left side of diaphragm 76 by conduit 78 increases, enabling rightward movement of diaphragm 76 in accordance with the force of spring 77. In consequence, lever 71 and cam 69 are pivoted clockwise about the axis of shaft 70 to enable an increased pumping stroke of diaphragm 40. Thus with decreased engine load, the pumping stroke of diaphragm 40 is decreased, the fuel flow pumped via conduit 28 into fuel bowl 16 is decreased, and recirculation of fuel to the bowl 16 is minimized. With increasing engine load, the increased pumping stroke enabled by diaphragm 40 increases the fuel flow via conduit 28 to fuel bowl 16.

Referring to FIGURE 2, another means for varying the effective stroke of the pumping diaphragm 40 is illustrated wherein cam 69, shaft 70 and lever 71 are omitted entirely. A wedge-shaped cam 79 is secured to the outer end of plunger 73 and is arranged to be inserted between pivotal lever 61 and cam 65 in accordance with movement of diaphragm 76. In other respects the structure and operation of the mechanism of FIGURE 2 is the same as in FIGURE 1, so that only a fragmentary portion is illustrated in FIGURE 2 and identical parts are numbered the same in both drawings.

In FIGURE 2 the spring urging upward movement of diaphragm 40 and corresponding to spring 44 will be under substantially no compression when the pivotal lever 61 is in the horizontal position shown. Accordingly the diaphragm 40 will be at the upper limit of its pumping stroke, as in FIGURE 1. It is apparent that upon rightward movement of wedge 79 between the left end of lever 61 and cam 65, the lost motion between arm 61 and enlargement 59 will be decreased and the downward spring compressing stroke of diaphragm 40 will be increased, thereby to increase the effective upward fuel pumping stroke of diaphragm 40. Thus with progressively increasing engine load and decreasing pressure of conduit 78, spring 77 will gradually urge plunger 73 and wedge 79 to the right between lever 61 and cam 65 so as to increase the effective pumping stroke and the fuel supply to the engine. It is also apparent that during low load operation of the engine, when throttle valve 12 moves to its closed position and the pressure in conduit 78 is a minimum, diaphragm 76 will be moved leftward to the

position shown in FIGURE 2 so as to withdraw wedge 79 from engagement between cam 65 and lever 61, thereby to minimize the fuel pumping stroke of diaphragm 40 and also to minimize the fuel pumped to bowl 16.

Although the structure of FIGURES 1 and 2 provide means for supplying fuel to bowl 16 at a rate which is a function of engine load, the vacuum induced force below valve 12 is at its maximum at low engine load and progressively decreases as engine load increases. Accordingly at comparatively high engine load when the throttle valve 12 is open fully or nearly so, the vacuum force acting on diaphragm 76 is a minimum. Thus changes in the throttle position result in comparatively low magnitude pressure changes on diaphragm 76.

Where increased effectiveness of the vacuum induced force at high engine load is desired, constructions such as illustrated in FIGURES 3 and 4 are preferred. The general arrangement of the return flow carburetor and pump is the same in FIGURES 3 and 4 as in FIGURES 1 and 2 so that identical parts are numbered the same in all views. The distinctions in FIGURE 3 over FIGURE 1 are that conduit 78 connects chamber 75 at the left of diaphragm 76 with the induction conduit adjacent the throat of venturi 11 and cam 69 is adjusted on shaft 70 so as to depress diaphragm 40 and limit its pumping stroke upon clockwise pivoting of lever 71 and cam 69. Upon counterclockwise pivoting of lever 71 and cam 69, the pumping stroke of diaphragm 40 urged by spring 49 is increased.

Accordingly as engine load increases, the vacuum induced force at the throat of venturi 11 increases and becomes a maximum at wide open throttle. The resulting low pressure at the left of diaphragm 76 results in leftward movement of diaphragm 76 and plunger 73 against the force of spring 77 to pivot lever 71 and cam 69 counterclockwise and increase the fuel pumping stroke of diaphragm 40. In consequence, as the airflow through venturi throat 11 increases with increasing engine load, the fuel flow into bowl 16 increases. Conversely as airflow through venturi throat 11 decreases with decreasing engine load, the vacuum induced force at the left of diaphragm 76 decreases, enabling spring 77 to pivot plunger 73 and lever 71 clockwise and decrease the pumping stroke of diaphragm 40, thereby to decrease the fuel flow into bowl 16.

In the FIGURE 3 construction, the vacuum induced force at the throat of venturi 11 becomes a minimum at low engine load. Accordingly where desired a dual control of the inlet fuel flow as illustrated in both FIGURES 1 and 3 may be employed to assure adequate operating force during conditions of both high and low engine loads.

FIGURE 4 shows a structure much like FIGURE 2 wherein lever 71, shaft 70 and cam 69 are eliminated, and wherein carburetor and fuel pump are the same as in FIGURE 3. In FIGURE 4, plunger 73 extends slidably and in fluid sealing engagement at 74a through the side wall of pressure chamber 75a and is provided with a wedge-shaped cam 79 as in FIGURE 2. Also in FIGURE 4, spring 77 is located at the right side of diaphragm 76 to urge the latter leftward. Diaphragm 76 partitions chamber 75a into two parts as in the earlier views, but in this instance, the left part of the chamber is vented to the atmosphere at 80. Conduit 78 is connected with chamber 75a at the right side of diaphragm 76 and is also connected with the induction conduit adjacent the throat of venturi 11 as in FIGURE 3.

With increased engine load and decreased pressure in conduit 78, diaphragm 76 is urged against the force of spring 77 to the right so as to insert wedge 70 between lever 61 and cam 65 and thereby increase the effective pumping stroke of diaphragm 40 as explained above in regard to FIGURE 2. Also as in FIGURE 2, the spring urging diaphragm 40 upward in FIGURE 4 is in its uncomressed condition when lever 61 is in the horizontal

position shown. Accordingly diaphragm 40 is at the upper limit of its pumping stroke in FIGURE 4. At low engine load and air flow through venturi 11, the increased pressure in conduit 78 enables spring 77 to urge diaphragm 76 and plunger 73 leftward, thereby to withdraw wedge 70 from between lever 61 and cam 65 to the position illustrated in FIGURE 4 whereas the pumping stroke is a minimum. Accordingly as in the FIGURE 2 construction, the pumping stroke of diaphragm 40 and the fuel supply to fuel bowl 16 is increased with increasing load. Conversely with decreasing load, the pumping stroke and the fuel supply to bowl 16 are decreased.

FIGURE 5 also illustrates a return flow carburetor and pump as described above wherein corresponding parts are numbered the same. In FIGURE 5, cam 69, shaft 70 and arm 71 are arranged as in FIGURE 1 to reduce the pumping stroke of diaphragm 40 upon counterclockwise pivoting of cam 69, and to increase the pumping stroke of diaphragm 40 upon clockwise pivoting of cam 69. In FIGURE 5, instead of employing the induction conduit pressure to control the movement of diaphragm 76 in accordance with engine load, a conduit 81 connects the upper right side of chamber 75 with the return flow conduit 52 at a location downstream of pumping chamber 43, thereby to regulate the pressure at the right of diaphragm 76 as a function of the return fuel flow. In order to accentuate the pressure changes in conduit 81, a restriction 82 is provided in conduit 52 at a location downstream of the latter's connection with conduit 81.

In accordance with the structure of FIGURE 5, when engine load and fuel consumption drop, the return flow through conduit 52 normally tends to increase. The increased return fuel flow is indicated by an increased pressure in the portion of conduit 52 between pumping chamber 43 and restriction 82. This pressure increase is transmitted by conduit 81 to diaphragm 76 to urge the latter leftward against the force of spring 77 and cause counterclockwise pivoting of lever 71 and cam 69 to progressively decrease the pumping stroke of diaphragm 40. Thus the fuel flow to bowl 16 is reduced and circulation of fuel through the bowl 16 is decreased until the latter fuel flow attains an equilibrium condition determined by the new engine load requirement.

It is also apparent that upon an increase in fuel consumption by the engine, the fuel return flow in conduit 52 will decrease and the pressure in conduit 81 acting on the right side of diaphragm 76 will likewise decrease, enabling spring 77 to urge diaphragm 76 rightward to pivot lever 71 and cam 69 clockwise. The pumping stroke of diaphragm 40 and the fuel flow to bowl 16 thus increase until the system again reaches the desired equilibrium condition determined by the fuel requirements at the new engine load. The foregoing structure is independent of pressure changes in the induction conduit and depends only upon the rate of return fuel flow in conduit 52, which is thus regulated to a desired nominal value during all conditions of engine operation.

FIGURE 6 illustrates a fragmentary portion of the carburetor and diaphragm pump of FIGURE 5 wherein cam 69, shaft 70, and lever 71 are omitted. In FIGURE 6 conduit 81 is connected with chamber 75a at the right of diaphragm 76 and also with the return flow conduit 52 downstream of pumping chamber 43 as in FIGURE 5. Chamber 75a is similar to the corresponding chamber of FIGURE 4, except that spring 77 in the left part of chamber 75a urges diaphragm 76 to the right. Port 80 vents the left side of chamber 75 to atmosphere. The plunger 73 extends rightwardly at 74a through the side wall of chamber 75a in fluid sealing engagement and is provided with a wedge-shaped cam 79 which is insertable between lever 61 and cam 65 upon rightward movement of plunger 73, as in FIGURES 2 and 4. In other respects, the structure and operation of the pump and carburetor mechanism are the same as in the above-de-

scribed views, so that corresponding parts are numbered the same.

During low engine loads when fuel consumption is low and the return flow fuel from chamber 43 is comparatively high, pressure in line 81 is high as described above and urges diaphragm 76 leftward against the force of spring 77 to withdraw wedge 79 from between lever 61 and cam 65. In this condition, the spring urging upward movement of diaphragm 40 in FIGURE 6 is not stressed when the lever 61 is in the horizontal position shown. Accordingly diaphragm 40 is at the upper limit of its pumping stroke and the pumping stroke will be a minimum during rotation of cam 65. As fuel consumption increases with increasing engine load, the return flow in line 52 drops and correspondingly the pressure in conduit 81 drops, enabling spring 77 to urge plunger 73 and wedge 79 to the right between lever 61 and cam 65. In consequence, the lost motion between lever 61 and enlargement 59 illustrated in FIGURE 5 is decreased and the effective pumping stroke of diaphragm 40 is increased so as to supply an increased quantity of fuel to the fuel bowl 16 with increasing engine load.

FIGURE 7 illustrates the return flow carburetor and pumping mechanism as in FIGURE 1 wherein corresponding parts are again numbered the same. In FIGURE 7 however, instead of controlling the pumping stroke of diaphragm 40 by induction conduit pressure as in FIGURES 1-4, or by return flow fuel pressure as in FIGURES 5 and 6, the pumping stroke is controlled by a mechanical linkage with the accelerator mechanism.

In FIGURE 7, pressure chamber 75 and vertical lever 71 are eliminated. A generally horizontal lever 83 is keyed at one end to a lateral external extension of cam shaft 70 which in turn is keyed to cam 69 overlying diaphragm 40 as in FIGURE 1. Cam 69 is disposed to enable increased upward pumping movement of diaphragm 40 when lever 83 is swung clockwise about the axis of shaft 70. The left end of shaft 83 is provided with a transverse pin 84 slidably secured within the yoke 85 of a pivotal shaft 86 pivotally mounted between its ends at 87 to a fixed portion of the carburetor casting 15. The left end of shaft 86 is pivotally connected at 88 to the upper end of a connecting link 89. The lower end of link 89 is pivotally connected at 90 to the outer swinging end of a crank arm 91 which in turn is keyed to an extension of valve shaft 13 exteriorly of the induction conduit 10.

Upon pivoting of crank arm 91, as for example by linkage 92 which is suitably connected with crank arm 91 and the customary pedal operated throttle mechanism, valve 12 is opened or closed. When crank arm 91 is pivoted clockwise, throttle valve 12 is progressively opened and link 89 is moved downward to swing lever 86 counterclockwise, thereby to pivot lever 83 clockwise about the axis of shaft 70 and raise the point of movement limiting engagement between diaphragm 40 and cam 69. In consequence, upon opening of throttle valve 12 during increased engine load, the pumping stroke of diaphragm 40 and the fuel flow to fuel bowl 16 are increased.

Upon counterclockwise or closing movement of valve 12 with decreasing engine load, lever 89 is moved upwardly, lever 86 is pivoted clockwise about the axis of pivot 87, and link 83 and cam 69 are pivoted counterclockwise to the position shown in FIGURE 7 to minimize the pumping stroke of diaphragm 40 and the fuel supply to bowl 16.

FIGURE 8 is concerned with a carburetor, pumping mechanism, and throttle actuated linkage including crank arm 91, links 86 and 89, and yoke 85, as in FIGURE 7, but wherein lever 83 and cam 69 are eliminated. A pin 93 slidably within yoke 85 in the manner of pin 84 of FIGURE 7 is secured to one end of a dog leg link 94 pivoted at 95 to a fixed bracket portion 37a of housing 37. The other end of dog leg link 94 comprises a vertical yoke 96 having a pin 97 slidably retained therein.

Pin 97 extends transversely through a generally horizontal extending shaft 98 having tapered wedge cam 79 at its left end arranged to be inserted between lever 61 and cam 65 as in FIGURES 2, 4, and 6. Shaft 98 is also slidably supported within bracket portion of housing 37a for horizontal movement.

Upon clockwise pivoting of crank arm 91 to open throttle valve 12, lever 86 is pivoted counterclockwise as aforesaid, causing dog leg link 94 to pivot clockwise and move wedge 79 between lever 61 and cam 65 to take up the lost motion between lever 61 and enlargement 59 and thereby to increase the effective pumping stroke of diaphragm 40 as described above in regard to FIGURES 2, 4, and 6. In this regard, the spring which urges upward pumping movement of diaphragm 40 will be determined so as to be in an unstressed condition when lever arm 61 is in the horizontal position illustrated. Thus diaphragm 40 will be at the upper limit of its pumping movement when wedge 79 is at the withdrawn position illustrated in FIGURE 8. As wedge 79 is moved rightward in FIGURE 8 upon opening of throttle 12 with increasing engine load, the effective pumping stroke of diaphragm 40 and the fuel supplied to bowl 16 is increased. Conversely as wedge 79 is withdrawn leftward upon closure of throttle 12 with decreasing load, the effective pumping stroke of diaphragm 40 and the fuel flow to bowl 16 is decreased.

Having thus described my invention, I claim:

1. In a carburetor for an internal combustion engine, movable wall-type pumping means for connecting a source of fuel with said carburetor, fuel flow control means for controlling the fuel flow to said carburetor, said pumping means having a reciprocable wall movable in alternate intake and pumping strokes, resilient means for yieldingly urging said wall in said pumping strokes, a pivotal actuating lever, means operatively connecting said lever and wall for alternately moving the same in said intake strokes in opposition to said resilient means and for releasing said wall for movement in said pumping strokes upon alternate pivoting of said lever in opposite directions, operable cam means for pivoting said lever in said opposite directions including a cyclical cam and adjustment means for varying the amplitude of said pumping strokes, said adjustment means operatively connecting said cam and lever to adjust the angular relationship of said lever with respect to said cam, and means responsive to operation of said fuel flow control means for actuating said adjustment means to increase the amplitude of said pumping strokes upon operation of said fuel flow control means to increase said fuel flow.

2. In a carburetor for an internal combustion engine, movable wall-type pumping means for connecting a source of fuel with said carburetor, said pumping means having a reciprocable wall movable in alternate intake and pumping strokes, resilient means for yieldingly urging said wall in said pumping strokes, a pivotal actuating lever, means operatively connecting said lever and wall for alternately moving the same in said intake strokes in opposition to said resilient means and for releasing said wall for movement in said pumping strokes upon alternate pivoting of said lever in opposite directions, the last named connecting means providing adjustable lost motion between said lever and wall for determining the extent of the latter's pumping stroke, operable cam means for pivoting said lever in said opposite directions including a cyclical cam and adjustment means for varying the amplitude of said pumping strokes, said adjustment means operatively connecting said cam and lever to adjust said lost motion, and means responsive to operation of said fuel flow control means for actuating said adjustment means to increase the amplitude of said pumping strokes upon operation of said fuel flow control means to increase said fuel flow.

3. In a carburetor for an internal combustion engine having an air intake manifold system, flow control means

for controlling the air flow in said system, movable wall type pumping means for connecting a source of fuel with said carburetor, said pumping means having a reciprocable wall movable in alternate intake and pumping strokes, resilient means for yieldingly urging said wall in said pumping strokes, a reciprocating member, means operatively connecting said member and wall for alternately moving the same in said intake strokes in opposition to said resilient means and for releasing said wall for movement in said pumping strokes upon alternate reciprocating of said member in opposite directions, adjustable movement limiting means engageable with said pumping means to limit the length of the pumping stroke thereof, and means responsive to operation of said flow control means and operatively connected with said movement limiting means to adjust the latter to increase said pumping stroke with increasing air flow in said system.

4. In a carburetor for an internal combustion engine having an air intake manifold system, flow control means for controlling the air flow in said system, movable wall type pumping means for connecting a source of fuel with said carburetor, said pumping means having a reciprocable wall movable in alternate intake and pumping strokes, resilient means for yieldingly urging said wall in said pumping strokes, a reciprocating member, means operatively connecting said member and wall for alternately moving the same in said intake strokes in opposition to said resilient means and for releasing said wall for movement in said pumping strokes upon alternate reciprocating of said member in opposite directions, operable cam means for reciprocating said member in said opposite directions including a cyclical cam and adjustment means for varying said pumping strokes, said adjustment means operatively connecting said cam and member to adjust the relative position of said member with respect to said cam, and means responsive to operation of said flow control means for actuating said adjustment means to increase said pumping stroke with increasing air flow in said system.

5. In combination, a carburetor for an internal combustion engine having an air intake manifold, a fuel bowl, duct means connecting said fuel bowl with said manifold for supplying fuel thereto, fuel flow control means for controlling the fuel flow from said bowl to said manifold, movable-wall type fuel pumping means connected with said bowl for supplying fuel thereto, means for maintaining the fuel in said bowl at a predetermined level comprising an overflow weir defining a sidewall portion of said bowl arranged for flow of excess fuel thereover when the fuel in said bowl attains said predetermined level, said pumping means having a reciprocable wall movable in alternate intake and pumping strokes, adjustable movement limiting means engageable with said pumping means to limit the length of said pumping strokes, and amplitude control means responsive to operation of said fuel flow control means and operatively connected with said limiting means to adjust the latter to increase the amplitude of said pumping strokes with increasing fuel flow from said bowl to said manifold, said pumping means including oscillating means operatively engageable with said wall for moving the same in said alternate intake and pumping strokes, cyclic cam means, said movement limiting means operatively connecting said cam and oscillating means for operating the latter to move said wall in said alternate intake and pumping strokes and being adjustable to increase the amplitude of said pumping strokes upon operation of said fuel-flow control means to increase said fuel flow.

6. In combination, a carburetor for an internal combustion engine having an air intake manifold, a fuel bowl, duct means connecting said fuel bowl with said manifold for supplying fuel thereto, fuel flow control means for controlling the fuel flow from said bowl to said manifold, movable-wall type fuel pumping means connected with said bowl for supplying fuel thereto, means for maintain-

ing the fuel in said bowl at a predetermined level comprising an overflow weir defining a sidewall portion of said bowl arranged for flow of excess fuel thereover when the fuel in said bowl attains said predetermined level, said pumping means having a reciprocable wall movable in alternate intake and pumping strokes, adjustable movement limiting means engageable with said pumping means to limit the length of said pumping strokes, and amplitude control means responsive to operation of said fuel flow control means and operatively connected with said limiting means to adjust the latter to increase the amplitude of said pumping strokes with increasing fuel flow from said bowl to said manifold, said intake manifold having a venturi throat therein, said duct means being connected with said intake manifold adjacent said throat for increasing the fuel supplied thereto with increasing air flow therein, said fuel control means including a throttle valve in said manifold downstream of said throat for controlling said air flow, said pumping means including oscillating means operatively engageable with said wall for moving the same in said alternate intake and pumping strokes, cyclic cam means, said movement limiting means operatively connecting said cam and oscillating means for
